UNITED STATES PATENT OFFICE.

EMMA K. MILLER, OF MILWAUKEE, WISCONSIN.

COLLAPSIBLE PAIL, COVER, AND DIPPER.

Application filed December 7, 1925. Serial No. 73,757.

This invention relates to buckets or pails and the primary object of the present invention is to provide a novel pail or bucket which can be collapsed to occupy a minimum amount of space during shipping or storage, or when the same is not in use.

Another object of the invention is the provision of novel means for holding the bucket in its extended operative position so as to preclude the collapsing thereof.

A further object of the invention is the provision of a novel cover for the bucket and novel means associated with the cover for receiving the means for holding the bucket in its operative extended position, when the bucket or pail has been collapsed.

A further object of the invention is the provision of novel means for associating a dipper therewith, so as to prevent loss of the dipper and to permit the ready association of the dipper with the bucket, when the bucket is in its collapsed condition so that a minimum amount of space will be occupied thereby.

A still further object of the invention is to provide an improved bucket of the above character which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, in which drawings:

Figure 1 is a side elevation of the improved bucket showing the same in its extended operative position,

Figure 2 is a similar view looking at right angles to Figure 1,

Figure 3 is a top plan view of the bucket showing the same in its collapsed position,

Figure 4 is a side elevation of the bucket showing the same in its collapsed position,

Figure 5 is an enlarged fragmentary section through the base of the bucket illustrating the means for associating the bases with the means utilized for holding the bucket in its extended operative position,

Figure 6 is an enlarged fragmentary section through the upper end of the bucket showing the novel cover associated therewith, and

Figure 7 is a detail perspective view of the

novel dipper, which is adapted to be associated with the bucket.

Referring to the drawings in detail, wherein similar reference characters designate corresponding parts throughout the several views the letter A generally indicates the improved collapsible bucket which comprises a base 10, a body 15, and a cover 30. The base 10 can be constructed from any desired material such as sheet metal or the like and includes a disk shaped plate 11 having a downwardly extending base flange 12 for resting on the ground or floor. The flange can have its lower end rolled as at 13 in order to prevent the forming of sharp edges and to provide an enlarged face for engaging the ground. The disk or plate 11 of the bottom 10 at diametrically opposed points is provided with pairs of sockets 14 for a purpose, which will be hereinafter more fully described.

The body 15 is of a collapsible nature and includes a bottom section 16 and a plurality of sections 17. The section 16 is of annular formation and is formed on or secured to the disk 11 of the bottom 10 in any desired way. It is to be noted that the section 16 gradually decreases in diameter toward its lower end. There can be as many sections 17 as desired and each of these sections are of annular construction gradually tapering toward their lower ends and each section gradually increases in size to permit the ready collapsing thereof, upon the lower section 16 and on the base or bottom 10. The meeting edges of the sections 16 and 17 can be provided with suitable beads, if preferred to provide a fluid type of joint or the sections can be constructed to frictionally contact with one another when the same are raised. The uppermost section 17 has secured thereto ears 18 to permit a bail carrying handle 19 to be associated therewith so that the bucket or pail can be readily carried full of water or the like. The opposite sides of the upper section 17 between the ears 18 are provided with a pair of outwardly extending ears 20 provided with suitable openings for receiving the U-shaped brace rod 21. Each of the U-shaped brace rods 21 include parallel legs 22 and a connecting bight portion 23. The legs 22 are adapted to be inserted through the openings formed in the ears 20 until the same engage the upper face of the base 10, and these legs are adapted to

fit within the socket 14 as clearly shown in Figure 5 of the drawings. In order to prevent displacement of the U-shaped brace member 21 when the same are placed in position leaf springs 24 are provided. These leaf springs are secured to the upper section 17 of the body between the ears 20 and adapted to engage the bight portions 24 of the said U-shaped braces.

10 When it is desired to collapse the bucket it is merely necessary to raise the leaf springs 24 and withdraw the braces from position and then press downward upon the sections 17.

15 A suitable cover 30 is provided for the bucket and the same is provided at its periphery with an inturned flange 31 for snugly engaging the upper section 17 as clearly shown in Figure 6 of the drawings. 20 This cover 30 can be provided with alined guides or eyes 32 for receiving the U-shaped braces 21 when the same are not in use, so as to prevent loss thereof. The cover 30 can also be provided with a suitable bail handle 25 33 rockably secured to the ears 34 connected with the cover. This permits the easy removing of the cover from the bucket.

30 The novel dipper B is also provided for the bucket and the dipper includes a bowl 40 having a socket 41 for removably receiving the handle 42 thereof. The outer end of the handle is provided with a suitable hook 43 as shown and the bowl 40 of the dipper can be provided with a hook 44. When the 35 bucket is in its collapsed position the handle 42 is removed from the bowl of the dipper and inserted through alined eyes or guides 40 carried by the cover while the bowl portion 40 of the dipper is placed within the collapsed body of the bucket with the hook 44 snapped over the upper edge thereof.

From the foregoing description, it can be

seen that I have provided a novel collapsible pail which is of exceptionally simple and durable character and which can be placed 45 upon the market at a reasonable cost.

Changes in details may be made without departing from the spirit or the scope of this invention, but—

What I claim as new is:

1. A pail comprising a base, a collapsible body arranged on the base including a plurality of annular sections gradually tapering toward their lower ends, the sections successively increasing in diameter relative to 50 one another to permit the same to be collapsed upon the base, a pail handle carried by the upper section, the base being provided with a pair of sockets at diametrically opposed points, laterally extending 55 ears carried by the uppermost sections, U-shaped brace rods detachably and slidably fitted within said ears for engaging the sockets when the body is in its extended operative position, and leaf springs for engaging 60 the upper ends of the brace rods to prevent accidental displacement thereof, upon said ears.

2. A pail comprising a base, a collapsible body arranged on the base including a plurality of annular sections gradually tapering toward their lower ends, the sections successively increasing in diameter relative to 70 one another to permit the same to be collapsed upon the base, the base being provided with sockets, laterally extending ears carried by the uppermost section, brace rods detachably and slidably fitted within said 75 ears for engaging the sockets when the body is in its extended position, and means 80 for engaging the brace rods to prevent accidental displacement thereof from said ears.

In testimony whereof I affix my signature.

EMMA K. MILLER.
